UNITED STATES PATENT OFFICE.

HOWARD J. HOEGG, OF WEATHERLY, PENNSYLVANIA.

MAGNETO PLUG.

1,410,251.

Specification of Letters Patent. Patented Mar. 21, 1922.

Application filed November 3, 1921. Serial No. 512,535.

To all whom it may concern:

Be it known that I, HOWARD J. HOEGG, a citizen of the United States of America, and resident of Weatherly, in the county of Carbon and State of Pennsylvania, have invented certain new and useful Improvements in Magneto Plugs, of which the following is a specification.

This invention relates to magneto plugs of special utility in connection with the construction embodied in the Ford automobile motor, and the said invention has for an object a provision of novel means whereby a plug of the character indicated may be conveniently installed and removed, a desirable feature when said plug is to be cleaned or adjusted, or when for any other reason it has to be removed.

It is a further object of this invention to provide a plug of the character indicated and in which the plug comprises a plurality of detachable parts, so connected together as to prevent rotation, one with relation to the other, when the fastening for holding the plug parts in assembled relation is being manipulated.

It is furthermore an object of this invention to produce a plug of the character indicated comprising comparatively few inexpensive parts which can be renewed, should they become worn or broken.

With the foregoing and other objects in view, the invention consists in the details of construction, and in the arrangement and combination of parts to be hereinafter more fully set forth and claimed.

In describing the invention in detail, reference will be had to the accompanying drawing forming part of this application, wherein like characters denote corresponding parts in the several views, and in which—

Figure 1 illustrates a view in elevation of a fragment of a motor conventionally shown, with a device embodying the invention applied thereto;

Figure 2 illustrates an enlarged detailed sectional view of the plug and its anchoring means;

Figure 3 illustrates a top plan view of the said plug and anchoring means;

Figure 4 illustrates a sectional view on a line corresponding with the line 4—4 of Fig. 2;

Figure 5 illustrates a sectional view on a

line corresponding with the line 5—5 of 55 Fig. 2;

Figure 6 illustrates a sectional view on a line corresponding with the line 6—6 of Fig. 2; and

Figure 7 illustrates a detailed view of a 60 slightly modified construction.

In these drawings 10 denotes a fragment of a crank case to which the magneto plugs on the type of automobile mentioned are installed. In applying the plug to the case, 65 an anchoring nut 11 has a threaded aperture of the size of the threaded portion of the plug, as will presently appear, and this anchoring nut is provided with a series of apertures 12 to receive fastenings such as screws, 70 although the manner of attaching the nut to the case may be changed to suit particular requirements. It is intended that the nut 11 shall be stationed on the crank case in position to permit the electrode of the 75 plug to enter the aperture usually formed in the crank case where the magneto plugs are now installed, and after the nut has been so anchored, the plug of this invention may be screwed into place or removed by unscrewing it in the same manner as spark 80 plugs are applied to cylinder heads of internal combustion motors.

In further explanation of the manner of carrying the invention into practice, it is 85 seen that the magneto plug comprises a body 14 of shell-like form, having a threaded nipple 15 which enters the threaded aperture of the nut 11. The top of the body 14 has an opening 16, the walls of 90 which are preferably angularly disposed, one with relation to the other, in order that they will conform to the configuration of the shoulders on the head 17 of an insulating bushing 18, which insulating bushing 95 fits within the body 14, as clearly shown in Fig. 2. The bushing has an apertured upper end, the end wall in which the aperture is formed being recessed as at 19, the wall of which recess is of irregular outline 100 to engage shoulders of a head 20. A threaded shank or post 21 is integral with the head and this post 21 projects through the aperture in the insulator and serves to retain the body, insulator and post in assembled relation to each other. The irregular configuration at the joints between the body and the insulator as well as be-

5 between the insulator and the head, serves to prevent rotation of any of these parts with relation to the other parts when the binding nut 22 is threaded on the post and the insulating washer 23 is forced by the nut into intimate contact with the top of the body to seal the joints between the elements at the top of the plug.

10 A yieldable electrode 24 in the nature of a coiled spring has one end secured to the head and this electrode is therefore removable with the post when the nut 22 disengages the threads of the post, and when this condition exists, the insulator as well 15 as the electrode and post may be dismantled from the body. The body has an irregular external surface, preferably octagonal, so that the shoulders may be engaged by a wrench or the like for screwing the plug 20 into the nut or for removing it, so that by the use of a wrench, the magneto plug may be applied or removed.

15 The modification shown in Fig. 7 comprises an electrode 25 having a contact point 26, the shank 27 of which extends into the convolutions of the coiled electrode, serving to hold the parts in assembled relation, and under some conditions, this contact point might prove more desirable than 20 the form illustrated in Fig. 2.

25 It will be apparent from an inspection of the drawing and from the foregoing description that the anchoring nut and magneto plug can be manufactured as commercial products to be installed on motors now in use, and that by having the apertures of the nut which receive the fastenings in such spaced relation to each other as now exists 30 in the magneto plug flanges which are secured to the automobile above mentioned, now in common use, this improved device 35 could be substituted for those plugs which require the removal of all of the anchoring screws or elements prior to the removal of 40 the plug. By reason of the fact that this plug is removable from the nut and that the insulation is effected by the bushing, it 45 is possible to produce this plug compara-

tively inexpensively, and it has been found to prove advantageous in practice.

50

I claim:

1. In a magneto plug for internal combustion motors, an anchoring member having an aperture the wall of which is threaded, means for anchoring the member 55 to a crank case, a body having a threaded nipple to engage the threads of the anchoring member, the said body being hollow and having an aperture in its head, the wall of which is of irregular contour, an insulating bushing open at one end and having an apertured head, the external surface of the head conforming to the configuration of the aperture in the body and fitted therein, the said apertured end of the bushing having 60 a seat with which the aperture merges, the said seat having a wall of irregular contour, a head fitted to the seat, a threaded shank carried by the head and projecting through the aperture of the bushing, a 65 member threaded on the shank, and an electrode secured to the head and projecting beyond the inner end of the bushing.

2. In a magneto plug, a member having an aperture the wall of which is threaded, 70 means for securing the member to a crank case, a plug body having a threaded portion engaging the threads of the anchoring member, the said plug body being open at 75 its inner end and having a shouldered aperture at the opposite end, a bushing having an external configuration fitting the shoulder and aperture of the body at the outer end, said bushing having an open inner end and an apertured outer end in the part extending through the aperture of the body, a terminal post projecting through the aperture of the bushing carrying a head, the said head being seated in the inner 80 wall of the bushing near its outer end and an electrode carried by the said head and removable from the bushing therewith, and means applied to the terminal post for holding the electrode and bushing in assembled 85 relation to the body.

HOWARD J. HOEGG.
